MORDICHA MARGOLITH, OF NEW YORK, N. Y.

WAISTBAND FOR TROUSERS AND METHOD OF MAKING THE SAME.

Application filed November 19, 1925. Serial No. 69,958.

My present invention relates generally to the manufacture of trousers and has particular reference to a construction and method of manufacture of the waist-band portion of the trousers.

Where I have attempted to manufacture and complete the waist-bands of trousers by providing a stiffening interlining and a separate primary lining, I have found that a great deal of labor, including much hand-work, is necessary in order to produce a finished construction which is not only of neat outward appearance but of firm, and workmanlike construction.

The use of a separate lining to cover the stiffening interlining necessitates many operations of stitching, both in the construction of the separate lining itself and in the process of properly associating this lining with the trousers with the stiffening lining therebetween. In general, the stiffening interlining must first be attached to the waist-band of the trousers, and after the stitching is concealed, the separate lining must be attached to the interior edge of the waist-band by hand-work so that the stitching will not mar the final appearance. Thereafter the lining is tacked down to completely cover the interlining and a curtain portion previously associated with the lining must then also be tacked down to the trousers.

It is among the principal objects of the present invention to construct a waist-band in a manner which will entail none of these lengthy and expensive operations, and which eliminates the necessity for a separate lining member, a curtain portion, and which simplifies the manufacture, and renders it less expensive, by necessitating only two stitching operations, neither of which are made by hand.

Another object of the invention is to simplify the manufacture still further by eliminating the necessity for separate loops to be attached to the outside of the waist-band in a well-known manner to accommodate the belt. More particularly, it is an object of the invention to construct the waist-band in such a manner that the belt may be slidably accommodated within a guiding space along the interior of the waist-band.

One feature of my invention lies in utilizing only one lining element instead of the usual two or three, and attaching it by two substantially parallel spaced lines of machine stitching directly to the trousers; and in

shaping this element in a particular manner which will not only lend sufficient reinforcement to the waist-band but will render its outward appearance extremely neat and workmanlike.

Another feature of the invention lies in providing the stiffening element or strip with spaced transverse slits extending between the lines of stitching to permit the belt to be passed into and out of selected slits so that it will occupy only selected portions of the guiding space.

A particular feature of the invention lies in arranging these slits in pairs which are disposed on opposite sides of selected portions of a waist-band so that the belt may be passed out of the guiding space and lie exposed along the interior of the waist-band at the selected portions so that the binding qualities of the belt with respect to the waist of the wearer are greatly increased, and so that take-up of the belt will not materially affect the outside contour of the waist-band.

In a preferred embodiment, the reinforcing or stiffening strip comprises two portions disposed on each side of the waist-band and terminating short of the rear vertical seam and front vertical opening of the trousers; and these portions are provided with slits adjacent to their ends so that the belt will lie exposed along those portions of the waist-band which includes said seam and said opening. I prefer also to provide a pair of slits at each side of the waist-band so that the belt may be exposed at these portions also whereby this exposure will occur at substantially 90° intervals.

Another object of the invention is to provide a method which may be used in conjunction with trousers wherein a separate waist-band portion is attached to the upper edge of the trousers without increasing the actual number of operations.

A further feature of the invention lies in attaching the reinforcing strip to the trousers in a manner which will simultaneously attach the waist-band portion to the trousers.

A still further feature lies in so attaching the strip that a portion thereof will serve as an integral curtain portion which will not only conceal one line of stitching but will increase the resemblance of my present construction to that of the usual well-known waist-band.

For the attainment of the foregoing objects and such other objects as may herein-

after appear or be pointed out, I have illustrated several forms of the invention in the accompanying drawings, in which,

Fig. 1 is a perspective view of the upper portion of a pair of trousers, showing my waist-band construction, and showing the belt in association therewith;

Fig. 2 is a cross-sectional view taken along the line 2—2 of Fig. 1;

10 Figs. 3 and 4 are views similar to Fig. 2, showing the invention as applied to trousers having separate waist-band portions; and

Fig. 5 is a view similar to Figs. 2, 3, and 4, showing a further modification.

15 Referring now to the drawings, and particularly to Figs. 1 and 2, I have shown a pair of trousers 10 having the usual front opening 11 and rear vertical seam 12. The stiffening strip comprises two portions 13 and 14 carried along the interior of the upper edge of the trousers and disposed on either side of the trousers, terminating at points short of the rear seam 12 and the front opening 11.

20 Reference to Fig. 2 will disclose clearly how the stiffening strips 13 and 14 are applied. The stiffening strip 14 is attached along one free edge thereof to the exterior of the upper free edge of the trousers 10 by a line of machine stitching 15. These free edges are then turned inwardly, preferably through 360°, to conceal the stitching 15 and the free edges, whereby the strip 14 will be brought into flat superposition over the trousers 10.

25 Thereupon a second line of stitching 16 is made along a line substantially parallel to the upper edge and to the line of stitching 15, thereby attaching the strip 14 directly to the trousers 10. The stitching 16 is preferably of a color substantially like that of the trousers material so that it will not be too conspicuous from the outside.

30 The lines of stitching 15 and 16 are spaced from each other so that a guiding space is provided underneath the strip 14 and between the two lines of stitching to slidably accommodate a belt 17. That is, the space for the belt is transversely limited in size by the lines of stitching 15 and 16. The

35 width of the strip 14 varies from a maximum at the rear of the trousers to a minimum at the front thereof, the maximum width extending a certain predetermined distance toward the front before the change in width takes place.

40 As clearly shown in Figs. 1 and 2, the maximum width of the strip 14 is approximately twice the distance between the stitches 15 and 16, and this width extends preferably from the rearmost end 18 of each

45 strip to a point 19 just rearward of the side of the trousers; continuing around toward the front, the width gradually decreases until a minimum is reached which is only slightly greater than the distance between the two lines of stitching. The additional

width of the strips 13 and 14 around the rear portion of the trousers serves not only to conceal the upper portions of the pockets 20, but adds firmness and reinforcement of a character which has not been possible heretofore in constructions wherein a stiffening interlining is covered over by an independent and separate lining.

50 In Fig. 3, I have illustratively shown how my construction and method of manufacture 75 may be applied to trousers embodying a separate waist-band portion. In such a case, the strip 14 is attached in a similar manner as described hereinbefore with reference to Fig. 2 to the upper edge of a waist-band 21; 80 and after turning the free edges inwardly, a line of stitching 16 serves to attach the strip 14 to the waist-band 21, and simultaneously to attach the waist-band to the upper edge of the trousers 10. In Fig. 3, I have shown 85 a preferred method of applying the line of stitching 16, wherein the upper edge 22 of the trousers 10 has been turned inwardly so that the line of stitching 16 will be invisible from the outside. Of course it will be evident that in this method of construction, the line of stitching 16 is so made as to attach the strip 14 and the waist-band 21 to the exterior of the upper edge 22, and thereafter the trousers material 10 is turned through 90 180° to conceal the stitches.

95 Fig. 4 shows a possible method of attaching these various elements together by the single line of stitching 16, which in this case is made to pass through to the outside 100 of the trousers material 10.

105 In Fig. 5, I have shown a construction which is substantially identical with that shown in Fig. 3, except that in this case I have formed a plait in the strip 14 along a line substantially overlying the line of stitching 16 which is subsequently to be made. This plait 23 is disposed away from the trousers 10 and the waist-band 21 to form three plies; and the line of stitching 110 16 is made to pass through only the two plies which are closest to these elements. In a construction of this character, the lower portion 24 of the strip 14 constitutes a curtain which will conceal the line of stitching 16 115 from the inside; and it will be obvious that in a construction of this character the line of stitching 16 is entirely concealed. I have stated in certain of the claims that the stiffening strip is plaited away from the trousers material, and in so doing I meant to cover the idea of plaiting in such manner that these plaits are produced at the expense of the lower part of said strip, the upper part of said strip being considered as fixed 120 at the upper edge of the trousers.

125 Referring again to Fig. 1, I have shown a plurality of transverse slits 25 which are preferably substantially perpendicular to the free edge, and which extend between the 130

lines of stitching 15 and 16. These slits are arranged in pairs, and a pair is arranged on opposite sides of each of the front, side, and rear portions of the waist-band. As a result, the belt 17 may be made to pass outwardly of the guiding space at the selected portions so that it will lie exposed within the waist-band as clearly shown in Fig. 1.

For the purpose of lending both strength and good appearance to the construction, I prefer to make the strips 13 and 14 of a material in the nature of canvas, and I prefer to cut the strips along a bias, that is, obliquely with the warp and weft threads of the canvas, so that a certain resilience is imparted thereto. By constructing the reinforcing strips 13 and 14 in two portions, I am enabled to leave the seam 12 free, so that the usual adjustments in the size of the waist-band may be made without interfering in any way with the waist-band construction, and without necessitating the detachment of either of the portions 13 and 14.

I prefer to utilize a belt made of canvas or other material having a roughened surface, because I have found that the exposure of the belt at the rear, front, and sides of the waist-band greatly improves its binding qualities with respect to the waist of the wearer. In other words, by permitting portions of the belt to contact directly with the usual shirt of the wearer, the shirt is not only prevented from riding upwardly out of the trousers, but the suspension qualities of the belt are greatly improved. At the same time, it will be obvious that no discomfort is afforded by this proximity of the belt because of the smooth unbroken internal contour of the waist-band. Moreover, an important advantage which is gained by permitting the belt to be exposed at these selected portions lies in the fact that take-up of the belt will not materially alter the contour of the waist-band, as is generally the case when the belt is arranged outside of the trousers. I have found that even in cases where the normal dimensions of the waist-band are too great for a given wearer, the trousers will be efficiently suspended without any crinkling thereof, the excess dimension manifesting itself only in a small gap between the exposed portions of the belt and the portions of the trousers corresponding thereto; from the outside, this gap is invisible and the trousers appear to fit perfectly.

It will be obvious that various changes in the details as herein described and illustrated for the purpose of explaining the nature of my invention may be made by those skilled in the art without departing from the spirit and scope of the invention as expressed in the appended claims, and it is

therefore intended that these details be interpreted as illustrative and not in a limiting sense.

I claim:—

1. The herein described method of making a waist-band for trousers, which comprises sewing together at their edges a stiffening strip and trousers material, the edges thereof projecting in the same direction, turning said strip over to the interior to conceal said stitches without folding said strip, and sewing said strip by a line of stitching directly to the trousers and at a distance from the aforesaid sewed edges sufficient to accommodate a slidable belt in the space between the strip and the trousers and between said stitches.

2. The herein described method of making a waist-band for trousers, which comprises sewing a stiffening strip along a free edge directly to the exterior of the upper free edge of the trousers, turning said strip over to the interior to conceal said stitches, sewing said strip without bending said stiffening strip directly to the trousers along a line of stitching parallel to the edge of the trousers and at a distance therefrom sufficient to accommodate a slidable belt in the space between the strip and the trousers and between said stitches, and providing spaced transverse slits in said strip extending between said lines of stitching to permit the belt to be passed into and out of selected slits and thereby occupy only selected portions of said space.

3. The herein described method of making a waist-band for trousers which comprises sewing a stiffening strip along a free edge of the trousers, turning said strip over to the interior to conceal said stitches without folding said strip, plaiting said strip away from the trousers material to form three plies along a line substantially parallel to and spaced from said edge, and sewing said strip directly to the trousers by a line of stitching substantially parallel to said edge and passing through the two plies nearest the trousers whereby the third ply will constitute a curtain to conceal said last-named stitching.

4. In a waist-band for trousers, a stiffening strip marginally carried along the interior upper edge of the trousers and attached thereto by two lines of stitching spaced from each other to form a transversely limited space between said stitches and underneath the strip, said space presenting only smooth surfaces to the belt and entirely free from projections therein, whereby said space may slidably accommodate and guide a belt.

In testimony whereof I affix my signature.
MORDICHA MARGOLITH.
